Attorney.

UNITED STATES PATENT OFFICE

WILLIAM J. McCAG, OF BUFFALO, NEW YORK, ASSIGNOR TO THE REPUBLIC METAL-WARE COMPANY, OF BUFFALO, NEW YORK, A CORPORATION OF NEW YORK

VENTILATING FAN

Application filed August 17, 1928, Serial No. 300,271. Renewed July 11, 1930.

This invention relates generally to fans of the circulating or ventilating type and more particularly to the means for controlling the discharge of air therefrom.

6 Its chief object is the provision of a reversible deflector for effectually controlling the radial discharge of air from the fan and directing it in a predetermined path or elevation desired by the user.

10 Another object of the invention is to provide a deflector of this character which is simple and inexpensive in construction, and which is readily adjustable by the user to meet his requirements.

15 In the accompanying drawings:—

Figure 1 is a side elevation of a fan showing my deflector thereon in one position. Figure 2 is an enlarged fragmentary vertical section thereof taken in the plane of line 2—2, Figure 1. Figure 3 is a similar view showing the deflector in a different position. Figure 4 is a top plan view of the fan.

20 Similar characters of reference indicate corresponding parts throughout the several 25 views.

By way of example, my improved deflector has been shown in connection with a desk type of ventilating fan comprising a base 10, an electric motor 11 supported in a vertical 30 position on the base and including a shaft 12 projecting upwardly therefrom, and a fan wheel including an inverted cone-shaped member or deflector 13 preferably of hollow form fixed on the motor-shaft to turn therewith and fan blades 14 radiating outwardly and downwardly from the flaring upper portion of said cone-shaped member and secured at their lower ends to a ring 15 surrounding the lower portion of the latter. When the fan 35 is rotated, the air will be thrust outwardly and upwardly by the centrifugal action created by the blades 14 in a direction controlled by the conical member 13 and the resulting suction produced at the center of the whirling column of air will draw the air inward to replace the displaced air.

Surrounding the fan-blades is a cage or 40 guard consisting of upper and lower rings 16, 17 and radially-disposed tie rods 18 extending around the bottom and sides of the fan

wheel and joined at their upper and lower ends to said rings in the manner shown in Figures 1 and 2. The lower ring may be attached to a collar 19 fixed to the upper end of the motor while the upper ring is supported by the tie rods and is disposed a suitable distance above the conical member 13.

55 Supported on the upper guard ring 16 directly over the top or flaring end of the conical member of the fan is a reversible supplementary deflector 20 which is designed to direct and spread the air circulated by the fan-blades outwardly in a more or less horizontal plane so that a gentle blast of air is brought at predetermined elevations to suit the desires of 60 the user.

In the preferred construction of the deflector shown in the drawings, the same comprises a hollow body 21 of frusto-conical form having convex top and bottom walls 22 and being of a diameter to extend beyond the 65 periphery of the upper end of the conoidal member 13, so that its annular marginal portions 23, 24 are disposed in the path of travel 70 of the air distributed by centrifugal force created by the blades 14 assisted by such conoidal member and serve to deflect the air in a greater or wider path and in a lower zone approximating the horizontal. In the inverted position of the deflector shown in Figure 75 2, wherein its larger, horizontal deflecting 80 surface or margin 23 is face downward, the air from the fan is deflected outwardly in a horizontal path with the blast of air circulated thereby striking the head of the user, if he be sitting, for example, at his desk. While 85 creating a desired circulation of the air at that elevation, it does not disturb the papers or other articles on the desk of the user. In the position of the deflector shown in Figure 90 3, wherein its upwardly-flaring portion 24 is disposed face downward, the air is deflected outwardly and slightly upwardly in a more or less contracted zone, as compared with that of its other position, with the blast of air circulating just above the head of the user or 95 thereabouts.

The deflector 20 is detachably mounted on the upper guard-ring 16 by means of a plurality of radial attaching lugs 25 having outwardly-facing notches 26 therein for engage- 100

ment with substantially upright bolts 27 welded or otherwise fastened to said guard ring. Arranged over the deflector is a guard frame 28 which likewise carries radial attaching lugs 29 for engagement with the bolts 27 whose nuts 30 serve to hold both the deflector and top guard firmly in place.

While this improved deflector is manifestly simple in construction, it effectively renders 10 the fan readily adjustable as to the desired direction of the air blast created by it to meet the conditions required of the user.

I claim as my invention:—

1. A ventilating fan, comprising a fan 15 wheel including a revolving deflector and blades carried thereby for diffusing the air outwardly and upwardly, and a supplementary deflector surmounting said fan wheel and adapted to be detachably supported in 20 different positions over said revolving deflector for directing the air at varying elevations and in a comparatively wide zone.

2. A ventilating fan, comprising a fan 25 wheel including a revolving deflector and blades carried thereby for diffusing the air outwardly and upwardly; and a reversible supplementary deflector surmounting said fan wheel and having deflecting surfaces on its opposite sides for directing the air lat- 30 erally at varying elevations.

3. A ventilating fan, comprising a fan 35 wheel including a revolving deflector and blades carried thereby for diffusing the air outwardly and upwardly, and a reversible supplementary deflector surmounting said fan wheel and having marginal deflecting surfaces on its opposite sides for directing the air laterally in predetermined paths and at varying elevations, said surfaces extending 40 beyond the periphery of the fan wheel deflector.

4. A ventilating fan, comprising a fan 45 wheel including a revolving deflector and blades carried thereby for diffusing the air outwardly and upwardly, and a reversible supplementary deflector surmounting said fan wheel and including a body portion and annular marginal deflecting surfaces at its 50 opposite sides for directing the air laterally in predetermined paths, one of said surfaces being horizontal and the other being inclined upwardly and outwardly.

5. A ventilating fan, comprising a fan 55 wheel including a revolving inverted conoidal deflector and blades radiating therefrom for diffusing the air outwardly and upwardly, and a reversible supplementary deflector surmounting said fan wheel and having convex top and bottom walls and annular marginal deflecting surfaces projecting outwardly 60 therefrom for directing the air diffused by the conoidal deflector laterally in predetermined paths, said surfaces extending beyond the periphery of said conoidal deflector, one 65 of such surfaces being disposed in a hori-

zontal plane and the other being inclined upwardly and outwardly.

6. A ventilating fan, comprising a fan 70 wheel including a revolving deflector and blades carried thereby for diffusing the air outwardly and upwardly, a guard frame for said fan wheel, and a reversible supplementary deflector supported on said guard frame above the fan wheel and having deflecting surfaces on its opposite sides for directing the air laterally in predetermined paths. 75

7. A ventilating fan, comprising a fan 80 wheel including a revolving deflector and blades carried thereby for diffusing the air outwardly and upwardly, a guard frame for 85 said fan wheel including a ring disposed above said deflector and having fastening elements rising therefrom, a supplementary deflector surmounting the fan wheel and adjustably suspended from said guard-ring, 90 said supplementary deflector having deflecting surfaces for directing the air laterally at varying elevations, and radial attaching lugs extending from the periphery of said supplementary deflector and engaging said fastening elements. 95

8. A deflector for ventilating fans, comprising a substantially frusto-conical body 100 having convex top and bottom walls, said body extending beyond the peripheries of said convex walls to provide upper and lower annular, marginal deflecting surfaces for directing the air laterally at different elevations in the normal and reversed positions of the deflector, respectively. 105
